Paul Geiger

Letters Patent

The Vocabulary referred to in these Letters Patent and making part of the same containing a description in the words of the said Paul Geiger himself of his Machine for breaking prints of trees or other hard substances.

A hoppier of iron worn in the form of a piston of a cone, with four iron cast to it two projecting from the top, and the other two from the base diametrically opposite each other. A cast iron nail of a pyramidal form elongated at the base so as to divide its diameter equally to about one-fourth of its length. When it begins to change its form from an octagonal into a quadrangular shape, beginning regularly to the top. The octagonal sides are forced out into teeth or ridges perpendicular to one another oblique to the other, which gives each prong a sharp edge. The nail is worked in a reciprocating motion, the intervening substance is with an increasing force broken against the side of the hoppier until small enough to fall through between it and the nail, which makes the two bridges or stays at the top and bottom of the hoppier. Two bridges or stays of wrought iron which extend across the top and bottom of the hoppier to the extremities of the iron, to which they are fastened by screws. The lower bridge or stay on which the nail turns is separated from the hoppier by plates of iron fastened of a sufficient thickness so as to afford a passage all round the hoppier for the broken substance to fall away. The shank of the nail passes through the lower bridge or stay in which it turns and is applied at the end to which the iron that turns it is applied.
